UNITED STATES PATENT OFFICE.

FRED K. HENDRICKSON, OF WORCESTER, MASSACHUSETTS, ASSIGNOR TO REED-
PRENTICE COMPANY, A CORPORATION OF MASSACHUSETTS.

PROFILING-MACHINE.

1,169,151.

Specification of Letters Patent. Patented Jan. 25, 1916.

Application filed June 9, 1915. Serial No. 33,203.

To all whom it may concern:

Be it known that I, FRED K. HENDRICKSON, a citizen of the United States, residing at Worcester, in the county of Worcester 5 and State of Massachusetts, have invented a new and useful Profiling-Machine, of which the following is a specification.

This invention relates to a profiling machine and particularly to a new and improved means for mounting and adjusting the guide pin or guide pin holder.

The principal objects of the invention are to simplify the supporting head which carries the profiling tool and also the guide pin 15 and yet provide a positive, simple, and readily accessible means for adjusting the guide pin, and one by which the same can be adjusted accurately by a single adjustment without resorting to any "cut and try" methods; to provide a construction in which although the guide pin holder, being adjustable, is not an integral part of the head, yet it is provided with a long bearing surface throughout the whole length of which it 25 intimately engages the head and this surface is on a curve so that it furnishes a support at points throughout a wide angle around the guide pin and thus substantially prevents chattering, and to provide a construction in which the guide pin holder, and especially its adjusting means, are arranged on the outside of the head and thus the location of any parts in front of them is avoided. In this way the parts are readily 30 accessible for adjustment, replacement, repair, or any other purpose.

The invention also involves other features of construction as will appear.

Reference is to be had to the accompanying drawings, in which—

Figure 1 is a horizontal sectional view of a portion of a profiling machine showing the main part of the supporting head in plan, but parts in horizontal section; Fig. 45 2 is a front elevation of the same; Fig. 3 is a plan of a portion of the head with the guide pin holder removed; Fig. 4 is a plan of the guide pin holder; Fig. 5 is a front elevation thereof; Fig. 6 is an end elevation 50 of the same; Fig. 7 is a front end elevation of the adjusting worm, and Fig. 8 is a side view of the same.

The invention is designed to be applied to an ordinary type of profiling machine and 55 for that reason the machine itself is not

shown. The head 10 which is designed to be mounted on a slide in the usual way is arranged as usual for supporting the profiling tool 11 and either one or two guide pins 12 as may be desired. In the present 60 case two of these pins are shown but the invention is equally applicable if only one is used. In order to have all the parts for supporting the guide pins on the outside of the head where they will be readily accessible 65 for all purposes and yet to provide a convenient and simple adjustment, the head is shown as provided with a flat horizontal shelf or projection 13, and below this projection is a space bounded on the inner side 70 by a curved wall 14. This curved wall constitutes a part of the surface and is intended to be machined to shape so that it may constitute a part of the support and assist in preserving the rigidity of the device as will 75 appear.

Near the outer corner of the projection 13 is a hole 15 for receiving a pivot pin 16. This pivot pin extends above and below the projection 13 and is shown as held in position by a set screw 17 or the like. Pivoted on the top and bottom projecting ends of this pin is a segmental guide pin holder 20. This holder has an arcuate outer surface 21 accurately machined to fit the curved surface 14 when the holder is in position. It will be seen that on account of this construction the holder, although made movable for the purpose of adjustment, is virtually a part of the head as it fits both above and below 80 the projection 13 and at its top and bottom surfaces and throughout the arc 14 is in intimate contact therewith. This makes the holder rigid and tends to prevent chattering. This holder is shown as provided with another perforation in which the guide pin 12 is secured. This is held in place firmly by means of a split boss and binding screw 22. Therefore the guide pin can move with the holder about the pivot 16. 95

Mounted on the front of the head is a removable plate 24 having a perforation 25 for the reception of the end of a wrench. Mounted in a socket in the edge of the head under this plate is a worm 26 having an 105 end socket for receiving the wrench. This registers with the perforation 25 and has threads which mesh with threads 27 located on a small arc on the guide pin holder and having the form of a fine threaded 110

worm gear. It will be obvious that by inserting the wrench and turning the worm the holder will be adjusted about the pivot 16 and consequently the guide pin will be 5 moved toward or from the profiling tool 11. It will be understood, of course, that this adjustment is very slight in practice.

The guide pin holder 20 is provided with a hole into which passes a binding screw 10 30. This binding screw is screw threaded into the lower portion of the holder and extends across the space between the two parts through a hole 31 which is larger than this screw and therefore permits of 15 the above mentioned adjustment. This screw is designed simply to be screwed down tight to hold the parts in their adjusted position.

Although I have described only one of 20 the guide pin holders above it will be understood that the description applies equally to the other one whenever that is used. It will be seen that by this construction of the guide pin holder, the means for 25 adjusting it, and the means for binding it are all located on the outside of the head where they are readily accessible and there is no possibility of having to get the guide pin holder out of adjustment in order to 30 clamp up or tighten the parts, or of having to get into an inconvenient position in order to make the adjustment or clamp the parts in position.

Furthermore although the guide pin 35 holder has to be made separate from the head in order to secure this adjustment, yet by having the long arcuate surfaces finished so as to fit snug at 14, rigidity is secured when everything is properly adjusted and 40 there are no small or weak parts that will interfere with this rigidity.

Although I have illustrated and described only a single embodiment of the invention, I am aware of the fact that many modifications can be made therein by any person skilled in the art without departing 45 from the scope of the invention as expressed in the claims. Therefore, I do not wish to be limited to all the details of construction herein shown and described, but—

What I do claim is:—

1. In a profiling machine, the combination with a supporting head having fixed means for guiding and holding a profiling 55 tool and provided with a horizontal shelf, of a guide pin holder pivoted on said shelf resting on its upper surface and projecting under its lower surface for supporting a guide pin, said holder being adapted to 60 guide the pin toward and from the profiling tool about said pivot for adjusting purposes.

2. In a profiling machine, the combination with a supporting head, having a curved surface on its outer side and provided with a projection extending to the center of the curve and a pivot on said projection, of a guide pin holder mounted to swing about said pivot and to fit said curved surface. 70

3. In a profiling machine, the combination with a supporting head having fixed means for guiding and holding a profiling tool, of a guide pin holder pivoted on said head for supporting a guide pin, said holder being adapted to swing the guide pin toward and from the profiling tool about said pivot for adjusting purposes and a binding screw carried by the holder for securing it in fixed position to the head. 80

4. In a profiling machine, the combination with a supporting head having fixed means for guiding and holding a profiling tool and provided with a horizontal projection and an arcuate surface extending from said projection, of a guide pin holder pivoted on said projection at the center of said arcuate surface and having means for supporting a guide pin, and a surface fitting said arcuate surface, said holder being adapted to swing toward and from the profiling tool about said pivot, while said surfaces are in contact. 85

5. In a profiling machine, the combination with a supporting head having a curved outer surface, a guide pin holder supported on said head and having a surface fitting said curved surface for steady- 95 ing the guide pin holder, and means for adjusting said guide pin holder along said 100 curved surface.

6. In a profiling machine, the combination with a supporting head, of a guide pin holder pivoted on said head and having a worm thread thereon concentric with the pivot thereof, and a worm carried by said head and meshing with said worm thread for turning the holder on its pivot. 105

7. In a profiling machine, the combination with a supporting head, of a guide pin holder pivoted on said head and having a worm thread thereon concentric with the pivot thereof, a worm carried by said head and meshing with said worm thread for turning the holder on its pivot, and a 110 plate on the front of the head holding said worm in position in the head, said worm having means accessibly located through said plate by which it can be turned and the holder adjusted. 120

In testimony whereof I have hereunto set my hand.

FRED K. HENDRICKSON.
